UNITED STATES PATENT OFFICE.

HENRY G. T. GLAZEBROOK, OF WOODHOUSE, ONTARIO, CANADA.

WAGON-RACK.

SPECIFICATION forming part of Letters Patent No. 355,262, dated December 28, 1886.

Application filed July 8, 1886. Serial No. 207,522. (No model.) Patented in Canada September 22, 1883, No. 17,726.

To all whom it may concern:

Be it known that I, HENRY G. T. GLAZEBROOK, of the township of Woodhouse, in the county of Norfolk, in the Province of Ontario, 5 Dominion of Canada, have invented certain new and useful Improvements in Wagon-Racks; and I do hereby declare that the following is a full, clear, and exact description of the construction and operation of the same, 10 reference being had to the accompanying drawings, forming part of this specification.

The invention relates, first, to a very simple, handy, and convenient rack of a peculiar construction which can easily and quickly be 15 placed on a common wagon-box, and becomes a combined wagon-box and hay-rack; second, it can also be adapted and applied, with a slight alteration, to the box of a common single or double democrat wagon and a frame- 20 work of hoops, &c., attached to the rack and covered with the usual canvas, oil-cloth, or kindred substance, so as to form a covered van.

The invention consists of an ordinary wagon- 25 box constructed with two-inch-plank sides and ends one foot high and one-and-one-fourth-inch-board floor, and a rack-frame made of six-inch boards provided with flat iron brackets bolted to the underside of the pieces forming 30 the frame. The said brackets are provided with square hooks, which rest on the sides of the box and serve to support the frame firmly thereon. When the said rack is fitted on the box, it becomes a useful and convenient com- 35 bined wagon-box and hay-rack.

In adapting it to a democrat wagon the rack is made a little shorter in front, the front end pieces removed a little farther back and serve as a driver's seat, and a light frame of hoops 40 or the equivalent fastened to the said rack and covered with cloth, canvas, oil-cloth, or kindred substance for protection from sun and rain, &c.

By reference to the drawings it will be seen 45 that Figure 1, Sheet 1, is an end elevation of my combined wagon-box and hay-rack. Fig. 2 is a plan view. Fig. 3 is a side elevation. Fig. 4 is a perspective view of one of the brackets detached. Fig. 5, Sheet 2, is a front 50 end elevation of the device with covered top

attached for a democrat. Fig. 6 is a side elevation of the same.

A, Fig. 1, Sheet 1, represents a section of an ordinary wagon-box with the sides and ends formed of two-inch plank and the bottom of 55 one and one-fourth-inch boards. The box will be about twelve feet eight inches inside, one foot high, and about three feet four inches wide.

B B are the side pieces of the rack-frame, 60 say about fifteen feet eight inches long, and C C the front and rear end pieces, about six feet four inches, making that the width of the outer portion of the frame. These pieces may be of pine, oak, or other wood and bolted at 65 a a a a, &c. A series of flat iron brackets, D, are bent at right angles, say about one and one-half inch wide and one-half an inch thick, one foot six inches long, and one foot six inches high. Each bracket is provided with a square- 70 shaped hook, E, about twelve inches from the bottom and six inches from the top. The brackets are bolted to the under side of the frame B C at regular intervals apart by bolts b b, secured by nuts. Every bracket is 75 strengthened by a brace, F, made of one-half-inch round iron and riveted to the bottom part of the bracket, and secured to the upper part by an eyebolt passing through it, (the bracket and rack-board,) as shown at Figs. 1 and 3. 80 The outer row of said eyebolts b have each a small hook, c, hanging at its end for convenience in attaching a rope for any required purpose.

d, &c., are the holes drilled in the bracket 85 for the bolts to pass through.

G is an oak cleat under the center of the box, secured at each end by a bolt and nut, e f, respectively, to the bottom of the wagon-box. The bolts e e are flattened above the bottom of 90 the box, and are made to pass up to and bend over the top of the sides to firmly secure the sides and bottom of the said wagon-box.

In placing the rack on a wagon, it is lifted up on the box until the square-shaped hooks E 95 of the brackets D hang upon the top edge of the box, the vertical portion of the bracket pressing on the outside of the box and the vertical portion of the said hook E pressing on the inside and holding the rack firmly in its 100

place, as seen clearly in the section, Fig. 1. The braces F being bolted to the lower end of the bracket and secured to the upper horizontal portion of the bracket gives ample support to 5 the side and end pieces of the rack.

When the rack is used on a wagon similar to those known as "democrats," the hooks e may be dispensed with, the side pieces, B, made somewhat shorter, and the front ends placed 10 close together a little back from the front ends of the side pieces to form a seat, g, and a light round top frame, H, fastened to the side pieces and covered with cloth, canvas, or oil-cloth I, as shown at Figs. 5 and 6, Sheet 2.

15 Having thus described my device, what I claim as my invention is—

1. The combination, with a wagon-box, of a series of brackets, D, constructed with a shoulder, E, and provided with braces F, the same 20 attached to a frame for a wagon-box rack, substantially as and for the purpose specified.

2. In a wagon-rack, the combination of the frame-pieces B B C C, and brackets D, all being constructed and arranged substantially as and for the purpose specified. 25

3. In a wagon-rack, the combination of the frame pieces B B C C, brackets D, box A, and hooks e, substantially as and for the purpose specified.

4. In a wagon-rack, the combination of the 30 frame-pieces B B C C, brackets D, box A, frame H, and top I, all constructed and arranged substantially as and for the purpose specified.

Dated at Simcoe this 9th day of June, A. D. 1886.

H. G. T. GLAZEBROOK.

In presence of—

J. H. ANSLEY,
G. E. JACKSON.
